MEMO BASE FOR PEN-INK UNITS

Bert M. Morris, Los Angeles, Calif.

Application April 26, 1944, Serial No. 532,863

5 Claims. (Cl. 120—1)

The invention relates to a memo base for a pen-ink unit and in particular to a receptacle or container adapted to house a memo pad and which is also adapted to serve as a base for a pen-ink unit of the general type shown in my U. S. Patent No. 2,188,828, patented January 30, 1940, for "Fountain inkwell."

An object of the invention is to provide a receptacle for holding a memo pad in close relation to the pen of the pen-ink unit, and particularly to provide a memo base or container which, except for a bottom piece, may be cast or molded in a single piece from suitable moldable material such as plastic.

Another object of the invention is to provide a memo base which facilitates removal of the sheets of paper forming the memo pad. This is accomplished by providing parallel sloping front and rear wall portions which support the paper fanned-out or with the upper sheets extending beyond the lower sheets.

Another object of the invention is to strengthen the base and to resist warping. This is accomplished through the provision of either or both the means which houses the memo pad and the means which accommodates the pen-ink unit.

For further details of the invention, reference may be made to the drawings wherein

Fig. 1 is a plan view of a base according to the present invention with a pen-ink unit of my former patent in position on the base.

Fig. 2 is a sectional view of line 2—2 of Fig. 1.

Figs. 3, 4 and 5 are plan views of modification of the base of Fig. 1.

Referring in detail to the drawings, while dimensions are not important, it is preferred that the various bases shown in the drawings be slightly larger than illustrated, in order that the bases in Figs. 1 and 5 may accommodate a memo pad 4" x 6", while the bases in Figs. 3 and 4 may accommodate a memo pad 3" x 5".

Referring to Figs. 1 and 2, the memo base 1, except for the bottom piece 2, comprises a single unitary piece of plastic having such a shape that it can be formed by casting or molding.

The base 1 has a top 3 which forms a support for the pen-ink unit 4 and which serves as the top of a compartment 5 adapted to house a memo pad in the form of a stack of loose sheets projecting with the paper fanned-out, that is, with the upper sheets projecting beyond the lower sheets and removable and insertable through the opening 6.

An intermediate portion 7 of the top 3 is provided with a ridge 8 having a somewhat egg-

shaped contour which fits the contour of the bottom of the pen-ink unit 4.

Integrally connected with the top 3 and supporting the same in the elevated position shown, is an inwardly sloping side wall 9 which extends around the top 3. The top 3 has a straight front edge 10. The sloping wall 9 as shown at 11 and 12 extends beyond the front of the edge 10 and the extensions 13 and 14 as shown at 13 and 14 respectively, extend inwardly parallel to the front edge 10. The extensions 13 and 14 are connected by a rib 15 and are spaced apart to provide a central opening 16 to provide a finger opening to facilitate inserting and removing the paper from compartment 5.

Each of the extensions 13 and 14 is in the form of a hollow wall of which the front wall portion comprises a continuation of the sloping wall 9. The rear wall portion 17 of the extension 13 slopes up and out, parallel to the front edge 18 of a plurality of ribs 19. Three or four ribs such as 19 may be provided under and across the width of the top 3, and each rib is in the form of a bracket having its upper horizontal side 20 integrally connected with the underside of the top 3, and having its vertical side 21 integrally connected with a cross partition or rib 22 which has a dimension cross-wise of the base 1 substantially that of the width of the paper to be stored in the compartment 5.

The sides of the compartment 5 comprise side wall portions, one of which is shown in elevation at 23 in Fig. 2. These side walls are shown in dotted lines at 23 in Fig. 1 and they extend from the sloping rear portions 17 and 17' of the front wall extensions 13 and 14, lengthwise of the base to the cross partition 22.

The bottom of the portions 17 and 17' and the connecting rib 15 are provided with a rabbet 24 and the cross partition 22 is provided with a similar rabbet 25, and the side walls 23 are provided with a similar rabbet not shown, to receive the four edges of a rectangular bottom piece 26 which may be of Celluloid or plastic material suitably secured to the rabbets by acetone or other adhesive.

At the rear of the base 1, the wall 9 extends above the level of the intermediate portion 7 of the top 3, to the ridge 8, and then it extends downwardly in a general direction as shown at 27 to form a pocket or recess 28 for the base of the pen-ink unit 4. The front and sides of this recess 28 which terminate in the ridge 8, are formed by a sloping wall 29 arising from the top 3. The underside of wall 29 slopes outwardly away from

the vertical wall 27, the underside of the space between the wall 27 and the sloping wall 9 likewise increases in taper downwardly, and the same is true of the taper between the front wall of extension 13 and the back wall 17 of the same extension and similarly for extension 14, to facilitate withdrawal of the die. This operation is further facilitated by arranging the front edge 10 of the top 3 to the rear of the bottom edge of the wall portions 17 and 17', and this offset likewise facilitates insertion and removal of the paper in the opening 6.

While the top 3 extends parallel to the bottom of base 1, to support the pen-ink unit 4 in a level position, a pleasing artistic effect is obtained by having the rear portion of the sloping wall 9 higher than the extensions 13 and 14, whereby the narrow ridge 30 which extends around to the ends of extensions 13 and 14, slopes downwardly as shown by the dotted line marked 30 in Fig. 2. A ridge 31 of similar width preferably extends the length of the front edge 10, and merges at its ends with the ridge 30. The ridge 8 is of similar width and merges with the ridge 30 at the rear of the base 1, as shown in Fig. 1.

The ridge 8, the cross partition 22 and the rib 19 all serve to strengthen the base 1, and particularly the top 3, which has no support along the front edge 10 except at the ends of the front edge 10 where it merges with the sloping wall 9 and on its underside with the side walls 23.

By spacing the front edge 10 of the top wall 3 back of the front wall extensions 13 and 14, space is provided whereby a short memorandum may be written on the upper side of the pad not shown, while the pad is in the compartment 5. If it is desired to write a longer memo, one or more sheets may be withdrawn through the opening 6, and the finger opening 16, as well as the lateral separation of the front edge 10 of the front wall portions 13 and 14, facilitate insertion and removal of the sheets of paper.

In the form shown in Fig. 1, the sides of the base 1 in front and back of the front edge 10, extend in a straight line parallel to each other and at right angles to the front edge 10, for a substantial distance. In the modification shown in Fig. 3, the base 32 is provided with sides 33 and 34 which taper outwardly in contour from the rear of the base towards the front thereof. Also the top 35 is provided with a front edge 36 which does not merge with the sides 33 and 34 as in Fig. 1, but instead it has angular extensions 37 and 38 which merge with the front wall extensions 39 and 40 respectively as shown at 41 and 42 respectively.

In the modification shown in Fig. 4, the base 43 is provided with sides 44 and 45 which curve outwardly from the rear towards the front and then inwardly to form the aligned spaced front wall portions 46 and 47 with which the front edge 48 of the top 49 merges as in Fig. 3.

Fig. 5 shows a further modification wherein the base 50 is provided with a top 51 having recesses 52 and 53 to accommodate two pen-ink units. As in the other figures, a portion of the top may be removed as shown at 54 and 55 as this removed material is not necessary. This leaves enough of the top to support the pen-ink unit at the narrow

shelf portion 56 and at the remaining portion 57 which is large enough so that advertising material or suitable legends may be applied thereto.

It will be apparent that various modifications may be made in the invention. For example, while it is preferred to employ the ridge 8 to define a recess which fits the base of the pen-ink unit, either the pen-ink unit may be left off of the base such as 1, or the ridge 8 may be omitted with or without the pen-ink unit, whereby the base 1 may either serve simply as a container for a memo pad without supporting the pen-ink unit, or it may do both, whether the ridge such as 8 is used or whether it is not.

I claim:

1. A memo base for a pen-ink unit, said base comprising a unitary casting having an elevated top having a front edge, said top being integrally united with a supporting wall extending around, beyond and parallel to the front edge of said top whereby the front edge of said top and the parallel portion of said wall provide an opening to the underside of said top, and partitions integral with the underside of said top and providing a pocket communicating with said opening, an intermediate portion of said top wall having a ridge enclosing a portion of said top wall, the contour of said ridge conforming to the base of a pen-ink unit, the rear side of said front wall sloping outwardly, and ribs under said top wall opposite said intermediate portion, the front edges of said ribs sloping parallel to the rear side of said front wall, and a bottom piece extending between said front wall and said ribs and secured thereto.
2. A receptacle comprising a unitary casting of moldable material having two spaced apart aligned front wall portions each comprising a hollow wall having front and rear portions spaced apart at the bottom and tapering upwardly to an apex, a top wall having a front edge spaced from said apex and forming an opening and cooperating wall portions under said top and forming a compartment for said opening, said front and top walls being free from undercut surfaces as seen from the top and from the bottom thereof to permit the draft of the die.
3. A container for holding a stack of loose sheets of paper with the upper sheets extending in front of the lower sheets, said container comprising a unitary casting having parallel outwardly sloping front and rear walls, a side wall integrally united with said front wall, a top wall integrally united with said side wall, said front wall having a finger opening, and said top wall having a front edge spaced apart from and extending parallel to said front wall to form an opening for a compartment for said sheets, the front edge of said top wall being offset rearwardly of the bottom of said front wall, and a bottom piece secured to said walls.
4. A container according to claim 3 wherein an intermediate portion of said top wall tapers inwardly in an upward direction and forms a ridge having a contour conforming in shape to the shape of a base of a pen-ink unit.
5. A memo base according to claim 1, wherein said parallel portion of said front wall has a finger opening.

BERT M. MORRIS.
